FLUOROCARBON ETHERS

Joseph H. Simons, State College, Pa., assignor to
Minnesota Mining & Manufacturing Company,
St. Paul, Minn., a corporation of Delaware

No Drawing. Application July 21, 1948,
Serial No. 39,999

6 Claims. (Cl. 260—614)

1

This application relates to the discovery of a new and useful class of highly stable synthetic fluorine-containing carbon compounds, the saturated aliphatic (acyclic) fluorocarbon ethers. This class includes the polyethers as well as the monoethers.

The monoethers have the generic formula:

where R and R' represent saturated aliphatic fluorocarbon radicals which may be the same or different. Saturated aliphatic fluorocarbon radicals are non-cyclic radicals consisting solely of carbon and fluorine atoms wherein the atoms are linked together by single interatomic valence bonds. These compounds correspond to the dialkyl ethers, the hydrogen atoms thereof being entirely replaced by fluorine atoms.

The simplest example, corresponding to dimethyl ether, is di-trifluoromethyl ether, CF_3-O-CF_3 . This compound is a gas and has a boiling point of about minus 59° C. The compound corresponding to diethyl ether is dipentafluoroethyl ether, $C_2F_5-O-C_2F_5$, a gas having a boiling point of about 1° C.

Compounds containing five or more carbon atoms in the molecule have boiling points above room temperature and hence are normally non-gaseous, as illustrated by di-n-heptafluoropropyl ether, normal $C_3F_7-O-C_3F_7$, a liquid having a boiling point of about 56° C. Compounds containing eight or more carbon atoms in the molecule have boiling points near to or above that of water and may be referred to as high-boiling compounds. Examples are normal $C_4F_9-O-C_4F_9$ (di-n-nonafluorobutyl ether), a liquid having a boiling point of about 101° C.; normal $C_5F_{11}-O-C_5F_{11}$ (di-n-undecafluoroamyl ether), a liquid having a boiling point of about 138° C.; and normal $C_6F_{13}-O-C_6F_{13}$ (di-n-tridecafluorohexyl ether), a liquid having a boiling point of about 179° C.

Unsymmetrical as well as symmetrical compounds are included. The lack of symmetry may arise from different numbers of carbon atoms in the side radicals, as in the case of $CF_3-O-C_2F_5$ (trifluoromethyl-pentafluoroethyl ether). Another type of non-symmetry exists where the radicals differ as to branching, as where one radical is branched and the other is a normal straight chain, illustrated by $C_2F_5-O-CF(CF_3)_2$, pentafluoroethyl-iso-heptafluoropropyl ether.

This invention includes not only the monoethers but also the saturated aliphatic fluorocar-

2

bon polyethers, which compounds contain two or more oxygen atoms. Examples are

(decafluoro-1,2-dimethoxy ethane), a normal gaseous compound having a boiling point of about 13° C.; and

(octadecafluoro diethylene glycol diethyl ether) a high-boiling liquid compound having a boiling point of about 97° C.

The saturated aliphatic fluorocarbon ether have physical and chemical properties which are in general quite different from those of the corresponding hydrocarbon ethers. They have a high degree of chemical inertness; they do not burn or react with oxygen; and they can be heated to high temperatures in "Pyrex" type laboratory glassware without reacting or decomposing. They do not react with metallic sodium or potassium except at elevated temperatures. They are colorless and are apparently substantially odorless when in pure form. They are water-insoluble. They separate out when mixed with liquid hydrogen fluoride, although the corresponding hydrocarbon ethers are quite soluble in the latter.

The boiling points are in all cases substantially lower than those of the corresponding hydrocarbon ethers, although the molecular weights are much higher, which may be illustrated by comparing the above figures with the boiling points of dimethyl ether (minus 25° C.) and normal dibutyl ether (141° C.).

These compounds have physical properties closely similar, in general, to those of the corresponding fluorocarbons having the same number of carbon atoms. The boiling points are of the same order, although the values are higher for the lowest members of the series and are lower for the higher members. Thus the boiling point of CF_3-O-CF_3 is about minus 59° C. and that of C_2F_5 is about minus 78° C.; while that of normal $C_4F_9-O-C_4F_9$ is about 101° C. and that of normal C_8F_{18} is about 104° C. This last point is surprising as it would presumably be expected that the boiling points would always be higher in view of the presence of the additional oxygen atom (or atoms) in the molecule.

These saturated aliphatic fluorocarbon ethers, in common with the fluorocarbons, have exceptionally low boiling points, low refractive indices, low dielectric constants, low viscosities and low surface tensions, relative to non-fluorin-

organic compounds of similar molecular weights.

These compounds have properties which permit of use for many of the purposes for which saturated fluorocarbons can be used. They may be employed as refrigerants, inert diluents for chemical reactions, solvents, fire extinguisher fluids, hydraulic mechanism fluids, heat transfer media, turbine impellants, transformer liquids, dielectrics, and lubricants; and as intermediates in the manufacture of other compounds.

The electrochemical process broadly described and claimed in my copending application, Ser. No. 677,407, filed June 17, 1946, (since abandoned in favor of Ser. No. 62,496, filed November 29, 1948), may be employed in preparing compounds of this invention. Briefly, this process involves electrolyzing an ether starting compound in liquid hydrogen fluoride, resulting in the formation of the corresponding saturated fluorocarbon ether, which can be readily separated and purified. Thus, for example, $C_2F_5-O-C_2F_5$ can be made by electrolyzing diethyl ether,

in liquid hydrogen fluoride.

It is not essential to use a hydrocarbon ether as the starting compound, as the latter can contain one or more carbon-bonded side or terminal atoms or radicals other than hydrogen which are replaceable by fluoride in the operation of the process.

An important sub-class of the compounds of the present invention, the members of which are particularly suited to efficient production by the aforesaid electrochemical process, consists of those compounds wherein each oxygen-bonded carbon atom is a constituent of a $-CF_2-$ group, each of which is also bonded to a carbon atom of a saturated fluorocarbon group. Thus each oxygen-bonded carbon atom is necessarily a "primary" carbon atom (one and only one other carbon atom being directly bonded to it). In the case of the monoethers this subclass may conveniently be represented by the generic formula:

where R and R' represent saturated aliphatic fluorocarbon radicals and may be the same or different.

The electrochemical process also produces as by-products various fragmentation products containing fewer carbon atoms than the parent compound, including fluorocarbon ethers of reduced carbon number, and also fluorocarbons resulting from breaking of the oxygen-carbon bonds in the case of some molecules.

A simple type of electrolytic cell can be used, employing a nickel anode and an iron or steel cathode, for example. An iron or steel container can be used, which may be employed as a cathode, with a cover of iron or steel which is bolted in place. Anode and cathode plates, in alternating array, can be suspended from the cover. A suitable gasket material, and insulating material for electrode mountings and leads, is "Teflon" (polytetrafluoroethylene). An upper outlet for gaseous products, an upper inlet for charging materials, and a bottom outlet for liquid products, may be provided. The cell may be provided with a cooling jacket for maintaining a desired operating temperature.

Commercial anhydrous liquid hydrogen fluoride can be used. This normally contains a trace of water, but water need not be present and highly anhydrous hydrogen fluoride can be used. Additional water can be present, but more than a few

percent will seriously reduce the operating efficiency. The ether starting compounds are soluble in this material.

A cell potential of about 4 to 8 volts has been found suitable. A current density of 20 or more amperes per square foot of anode surface can readily be obtained. Voltages sufficiently high to result in the formation of free fluorine are avoided. The process does not depend upon the generation of free fluorine and the latter, if produced, would result in explosions, electrode corrosion, and undesirable reactions.

A preferred operating pressure is atmospheric pressure and a preferred operating temperature is about 0° C.; but higher and lower operating pressures and temperatures can be employed.

When a gaseous fluorocarbon ether product is being made, it can be withdrawn with and separated from the other gaseous products of the cell. Liquid fluorocarbon ether products separate as a constituent of a liquid which is immiscible with the electrolyte and settles to the bottom of the cell from which it can be withdrawn. The fluorocarbon ether compound can be separated by fractional distillation. Higher product compounds which are in the solid range, likewise will separate from the electrolyte and can be removed.

Example 1

This example illustrates the production of the gaseous fluorocarbon ethers, CF_3-O-CF_3 and $C_2F_5-O-C_2F_5$, using dimethyl ether and diethyl ether, respectively, as the starting compounds in the previously mentioned type of electrochemical process.

Use was made of an iron laboratory cell containing a set of nickel anodes and iron cathodes, operating at atmospheric pressure and a temperature of 0°. About 200 grams of the ether starting compound was dissolved in about 1800 grams of anhydrous liquid hydrogen fluoride. The solutions were electrolytically conductive and at the operating cell voltage, in the range of 4 to 6 volts D. C., a current density of about 20 amperes per square foot of anode surface was obtained. Additions of the starting compound were made to replenish that consumed.

The mixture of gaseous products of the cell was led through a low-temperature condenser (-40° C.) to condense out most of the HF present in the mixture, then through an aqueous calcium chloride bubbler to remove remaining traces of HF, then through an aqueous potassium-sulfite-iodide bubbler to remove traces of OF_2 , then through an aqueous potassium hydroxide bubbler to remove traces of CO_2 , then through a dry potassium hydroxide tower to remove traces of water, and then through a liquid air trap to separate the hydrogen from the therein condensed compounds.

The product collected in the liquid air trap was subjected to low-temperature fractional distillation and the fluorocarbon ether fraction was thus isolated and was identified. The molecular weights were determined by the vapor density method. The measured boiling point and molecular weight values for the respective fluorocarbon ether products are:

	CF_3-O-CF_3	$C_2F_5-O-C_2F_5$
Boiling point.....°C.....	-59	1
Molecular weight (found).....	154	254
Molecular weight (calc.).....	154	254

The identification of these compounds has also been confirmed by mass spectrograph analyses which admit of no doubt, since the mass numbers of the ionic fragments can be measured with high precision.

Example 2

400 grams of di-n-butyl ether was dissolved in 1800 grams of anhydrous liquid hydrogen fluoride and electrolyzed in the same manner as in the preceding example, with additional ether being added to replenish that consumed. At the end of 60 hours, 1355 grams of immiscible liquid was removed from the bottom of the cell, and this was washed with potassium hydroxide solution to remove traces of HF, and then fractionally distilled to yield a liquid fraction which was identified as relatively pure normal $C_4F_9-O-C_4F_9$. This fraction had the following measured properties:

Boiling point (at 741 mm.) $^{\circ}\text{C}$ 100.7
Refractive index (at 25° C.) 1.261
Density (grams/c. c. at 34° C.) 1.689
Dielectric constant (at 20° C.) 1.82
Molecular weight 459

The molecular weight for the pure compound, calculated from the formula, is 454.

This compound has boiling point, refractive index, and density values which are slightly but appreciably lower than those of the normal C_8F_{18} fluorocarbon compound which have been found to be 104° C., 1.267, and 1.765, respectively, and may be compared with the values given above. The formula weight of C_8F_{18} is 438.

Example 3

Di-n-amyl ether was electrolyzed in anhydrous liquid hydrogen fluoride in the same manner and fractional distillation of the cell deposit resulted in a main liquid fraction identified as relatively pure normal $C_5F_{11}-O-C_5F_{11}$, having the following measured properties:

Boiling point (at 755.6 mm.) $^{\circ}\text{C}$ 138.4
Refractive index (at 25° C.) 1.268
Density (at 35° C.) 1.758
Dielectric constant (at 20° C.) 1.86
Molecular weight 553

The calculated molecular weight of the pure compound is 554.

Example 4

Di-n-hexyl ether was electrolyzed in anhydrous liquid hydrogen fluoride in the same manner and fractional distillation of the cell deposit resulted in a main liquid fraction identified as relatively pure normal $C_6F_{13}-O-C_6F_{13}$, having the following measured properties:

Boiling point $^{\circ}\text{C}$ 179
Refractive index (at 25° C.) 1.278
Density (at 28.5° C.) 1.803
Molecular weight 657

The calculated molecular weight of the pure compound is 654.

Example 5

185 grams of ethylene glycol monobutyl ether, $C_4H_9-O-CH_2CH_2OH$, was dissolved in 2000 grams of anhydrous liquid hydrogen fluoride and electrolyzed in the same manner as in the preceding examples. An additional 210 grams of the starting compound was added during the run to maintain conductivity. After 62 hours, 396

grams of material had collected in the liquid air trap (see the description of the gaseous products train in Example 1), and this was fractionally distilled to yield a liquid fraction which was identified as relatively pure nonafluorobutyl-trifluoromethyl ether, $C_4F_9-O-CF_3$, having the following measured properties:

Boiling point (at 742.8 mm.) $^{\circ}\text{C}$ 35.4
Refractive index (at 27° C.) 1.240
Density (at 27° C.) 1.581
Molecular weight 303

The calculated molecular weight of the pure compound is 304.

15 This example illustrates the use of a starting ether compound other than a hydrocarbon ether, since the compound has a terminal hydroxyl group and is both an ether and an alcohol. It also illustrates the obtaining of a fluorocarbon ether product compound having fewer carbon atoms than the starting compound.

In addition to the foregoing, it was found that 92 grams of immiscible liquid collected at the bottom of the cell, which presumably contained fluorocarbon ethers.

20 *Example 6*
83 grams of 1,4-dioxane (diethylene dioxide):

35 was dissolved in 2000 grams of anhydrous liquid hydrogen fluoride and electrolyzed in the same manner, an additional 238 grams of the dioxane being added during the 44 run period to maintain conductivity. The run produced 392 grams of material collected in the liquid air trap, which was fractionally distilled to yield a normally gaseous 40 gram fraction having a boiling point of 13° C. and a molecular weight of 269, which was identified as relatively pure

The latter has a formula weight of 270, in close agreement with the measured molecular weight determined from the vapor density. This example illustrates the production of an aliphatic 50 polyether by a process which involves the breaking of a cyclic starting compound.

Example 7

55 100 grams of diethylene glycol diethyl ether (diethyl carbitol)

was dissolved in 2000 grams of anhydrous liquid hydrogen fluoride and electrolyzed in the same 60 manner, an additional 300 grams of the ether starting compound being added during the 48 hour run to maintain conductivity. The run produced 307 grams of condensate in the liquid air trap, and 171 grams of immiscible liquid collected in the bottom of the cell. The latter was fractionally distilled to yield a 45 gram liquid fraction which was identified as relatively pure

70 corresponding to the starting compound but having all hydrogen atoms replaced by fluorine atoms. This fraction had the following measured properties:

Boiling point (at 737 mm.) $^{\circ}\text{C}$ 96.6
75 Refractive index (at 30° C.) 1.250

Density (at 28.5° C.) 1.617
 Freezing point (crystals) °C. -45
 Molecular weight 488

The calculated molecular weight of the pure compound is 486.

It was found that the infra-red absorption spectra of the foregoing products in each case revealed strong carbon-fluorine bands and indicated that the material was fully saturated and contained no hydrogen, thus further substantiating the identifications.

The following experiments demonstrate that the fluorocarbon ethers are quite stable in aqueous solutions of bases and mineral acids:

(1) 20 cc. of a 10% aqueous sodium hydroxide solution was placed in a 200 cc. glass ampoule. The solution was degassed and the ampoule evacuated, and then 3.3 grams of $\text{CF}_3\text{---O---CF}_3$ (di-trifluoromethyl ether) was introduced and the ampoule was sealed and then allowed to stand at room temperature for several days. The ampoule was opened and the solution was titrated for hydrolyzed fluoride. There was no detectable fluoride ion (F^-) in the solution, showing that the fluorocarbon ether had not become hydrolyzed to any detectable degree.

(2) The experiment was repeated except that a 10% hydrochloric acid (HCl) solution was used, and 3.4 grams of the fluorocarbon ether was introduced. The solution was found to contain approximately 0.13 milligram of fluoride ion per gram of the fluorocarbon ether, corresponding to less than 0.02% of the total fluorine.

(3) The experiment was again repeated except that a 10% hydriodic acid (HI) solution was used, and 3.0 grams of the fluorocarbon ether was introduced. The solution was found to contain approximately 0.14 mg. of fluoride ion per gram of the fluorocarbon ether, corresponding to less than 0.02% of the total fluorine.

As a measure of the reactivity of the fluorocarbon ethers, a determination was made of the solubility of the gas boron trifluoride (BF_3) in $\text{C}_4\text{F}_9\text{---O---C}_4\text{F}_9$ (di - n-nonafluorobutyl ether). Hydrocarbon ethers form stable compounds with

this gas, dissolving much more than 1 mol of BF_3 per mol of ether at room temperature. It was found that the solubility in the fluorocarbon ether at room temperature is about 0.01 mol per 5 mol of $\text{C}_4\text{F}_9\text{---O---C}_4\text{F}_9$.

Having described various embodiments of the invention, for purposes of illustration rather than limitation, what I claim is as follows:

1. As new and useful compositions of matter, 10 saturated aliphatic fluorocarbon ethers.
2. Saturated aliphatic fluorocarbon ethers having at least five carbon atoms in the molecule.
3. High-boiling saturated aliphatic fluorocarbon ethers having at least eight carbon atoms in 15 the molecule.
4. The new and useful fluorocarbon ether compounds having the formula:

20 where R and R' represent saturated aliphatic fluorocarbon radicals.

5. As new and useful compositions of matter, 25 saturated aliphatic fluorocarbon polyethers.

6. As new and useful compositions of matter, 30 saturated aliphatic fluorocarbon ethers having from one to three oxygen atoms and from five to twelve carbon atoms in the molecule, each oxygen-bonded carbon atom being directly bonded to one and only one other carbon atom.
